TEMPERATURE CONTROL THERMOSTATIC
SWITCH DEVICE

Victor Weber and William S. Kunzler, Greensburg, Pa., assignors to Robertshaw-Fulton Controls Company, Greensburg, Pa., a corporation of Delaware

Continuation of application Serial No. 648,780, February 19, 1946. This application December 27, 1948, Serial No. 67,532

10 Claims. (Cl. 219—39)

1

This invention relates to control devices and, more particularly, to condition responsive controls for electrically driven apparatus such as clothes dryers. This application is a continuation of our copending application, Serial No. 648,780 filed February 19, 1946 now abandoned.

Appliances of this nature may include a motor driven shell or drum in which the clothes are placed and an electrical heating element from which heated air may be circulated by a fan or blower throughout the load of clothing which is undergoing the drying operation. It is apparent that considerable latent heat remains in the load upon completion of the drying operation although the heating element has been cut off. Hence, the load cannot be removed from the appliance with safety until after a cooling-down period which should not be too prolonged.

An object of this invention is to render the control of the clothes drying operation fully automatic after the starting operation is accomplished.

Another object of the invention is to ensure a predetermined cooling-down period before the drying operation is completed.

Another object of the invention is to further dry the load of clothing during the cooling-down period.

Another object of the invention is to eliminate the possibility of damage to the clothing should the appliance become unattended after being started.

Another object of the invention is to require a manual resetting operation to again place the appliance in full operation after an initial heating cycle.

Other objects and advantages will become apparent from the following description taken in connection with the accompanying drawings, wherein:

Fig. 1 is a front elevation of the heat control device;

Fig. 2 is a side elevation with portions of the cover of the device broken away to show the inside structure;

Fig. 3 is a front elevation similar to Fig. 1 but with the front cover removed;

Fig. 4 is a rear elevation of the device with the rear cover removed;

Fig. 5 is a side elevation similar to Fig. 2 but showing other details of construction;

Fig. 6 is a partial enlarged section taken on the line VI—VI of Fig. 3;

Fig. 7 is a section taken on the line VII—VII of Fig. 1; and

2

Fig. 8 is a wiring diagram.

Referring more particularly to the drawings, a main housing for the heat control structure comprises an L-shaped frame 10 to which is secured by the screws 12 a channel-shaped cover 14. The arrangement provides a housing having an open end within which a block 16 of insulating material is secured by means of the screws 18. As shown in Fig. 5, the frame 10 is adapted to be fastened to an accessible portion of the appliance (not shown) by means of the lugs 20 through which suitable securing means may project.

The cover 14 is provided with a centrally located boss 22 having an axial opening in which a spud-piece 24 is secured and projects outwardly of the cover 14. Journalled on the spud-piece 24 is a bushing 26 carrying a handle 28 having a dial 30 thereon. The dial 30 carries indicia representing the various heating positions together with an "off" position all of which cooperate with a stationary reference point 32 formed on an escutcheon plate 34 which surrounds the dial 30 and is secured to the cover 14 by a bracket 36.

The handle 28 is non-rotatably mounted on the bushing 26 by cooperation with a cam element 38 which, as shown more clearly in Fig. 5, is formed on the bushing 26 intermediate the ends thereof. The handle 28 is provided with a recess 40 on the inner face thereof which interlocks with the cam element 38 to prevent relative rotation between the handle and the bushing. The cam element 38 is adapted for engagement with an operating bar 42 upon rotation of the handle 28 to "off" position. The bar 42 projects from the interior of the cover 14 through the boss 22 thereon and is slidably supported adjacent the cam element 38 by a portion of the bracket 36. The cam element 38 is provided with a stepped portion 44 with which the operating bar 42 is adapted for engagement to prevent further rotation of the handle 28 in a clockwise direction beyond the "off" position. The operating bar 42 is normally urged outwardly of the cover 14 by a leaf spring 46 secured to the front wall of the cover 14 and extending through a slot formed in the operating bar 42 as shown in Fig. 5.

The spud-piece 24 also carries a threaded element or stud 48 having a detent 50 projecting laterally from one end and cooperating with a slot 52 formed in the bushing 26 to prevent relative rotation. The inner end of the stud 48 supports an expandable and contractible diaphragm 54 and serves to move the diaphragm relative to the cover 14 upon rotation of the handle 28. The interior of the diaphragm 54 is in communication

with a capillary tube 56 which is partly coiled inside the boss 22 and extends therefrom exterior of the cover 14 where it is secured by the clamp 58. The tube 56 communicates with a condition sensitive bulb 60 which is adapted to be positioned at the point where the condition such as temperature is to be controlled. As is customary in such devices, a contractile and expansible liquid is provided in the bulb 60 and the capillary tube 56 so that upon expansion of the liquid as a result of the heat to which the bulb is subjected the liquid will be forced through the tube into the expansible and contractile diaphragm thereby actuating it to a sufficient extent to operate parts now to be described.

A button 62 provided on the face of the diaphragm 54 opposite the stud 48 abuts a depression formed in a main actuating lever 64. This lever, which is generally of U-shaped conformation, is provided with a knife-edge 66 serving to connect the legs of the U-shaped lever and which is seated in a knife-edged bearing 68 formed on a bracket 70 secured to the inner wall of the L-shaped frame 10. The base of the main actuating lever 64 is recessed at the center portion to provide a seat for one end of a tension spring 72, the other end of which is hooked in an aperture formed in the center cross bar 74 of an R-shaped control lever 76.

The two legs 78 and 80 of the control lever 76 are provided with knife edges cooperating with spaced knife-edged bearings 82 formed in a channel-shaped support 84 extending substantially parallel with the base of the frame 10. As shown more clearly in Fig. 6, the support 84 carries projections 86 which are loosely mounted in the wall of the L-shaped frame 10 adjacent the base thereof and serve to retain the support in position at one end thereof. Lateral displacement of the control lever 76 is prevented by a bracket 90 carried by the inner wall of the frame 10 and having arms projecting on each side of the legs 78 and 80. The support 84 also carries at the front end an adjusting screw 88 which may be adjusted to raise or lower the support 84 and change the tension of the spring 72 as desired.

An inverted V-shaped take-up arm 92 is attached to the control lever 76 rearwardly thereof by means of forwardly projecting spaced lugs 94 suitably notched for engagement with oppositely disposed shoulders 96 formed on the legs 78 and 80 of the control lever 76. The take-up arm 92 is further provided at the opposite end with a hook 98 which extends around the underside of the cross-bar of the R-shaped control lever 76 at the central portion thereof. The hook 98 limits the movement of the take-up arm 92 with respect to the control lever 76 and cooperates with the lugs 94 to attach it thereto.

The take-up arm 92 extends laterally beyond the cross-bar of the control lever 76 and carries a contact block 100 of insulating material mounted thereon for restricted pivotal movement in a horizontal plane. A contact bridge 102 is secured to the rear face of the contact block 100 for cooperation with contacts 104, 106 mounted on the insulating block 16 and projecting exteriorly of the cover 14. It will be observed that in this embodiment the contact 104 is provided with terminal connections including the screw 108 while the contact 106 is adapted for permanent connection with a conductor 110. It will be apparent, however, that such arrangement can be modified as dictated by the circuit arrange-

ment with which the control apparatus is used.

The structure so far described constitutes a snap action mechanism by means of which the control lever 76 can effect contact operation. Thus, as the liquid in the bulb 60 and the capillary tube 56 expands in response to temperatures prevailing at the point where the bulb is located, the diaphragm 54 will also expand and urge the free end of the main actuating lever 64 toward the knife-edged bearing 82 of the control lever 76. Due to tension of the spring 72, the control lever 76 and its companion take-up arm 92 will be moved to the right as viewed in Fig. 2 with a snap action as the actuating lever 64 moves overcenter past a line between the respective bearings of the two levers. Such snap action causes engagement of the contact bridge 102 and the contacts 104, 106, as will be apparent.

The closed position of the contacts 102, 104 and 106 will continue until the diaphragm 54 starts to contract upon cooling of the bulb 60 whereupon a similar over center snap action will occur but in the opposite direction to cause contact disengagement as the contact lever 76 resumes its normal position as shown in Fig. 2. Separation of the levers 64 and 76 under bias of the spring 72 is prevented by a limit stop member 109 which is secured to the insulating block 16 and extends into the path of movement of the lever 76.

Additional contacts are provided for support by the insulating block 16 and are located to one side of the contacts 104, 106. These contacts 112 and 114, respectively. The conductor 110 connects contact 109 with contact 112 permanently, while contact 114 is similar to contact 108 in having a terminal connection including a screw 116. The contacts 104, 106 which, as stated, cooperate with the contact bridge 102 are also provided with back contacts 118 and 120, respectively. The back contacts 118, 120 and the contacts 112, 114 cooperate with a pair of contact bridges 122, 124, respectively.

The contact bridges 122, 124 are mounted upon separate insulating plates 126 carried by flexible members 128 upon the opposite bifurcated ends of a secondary lever 130. The secondary lever 130 extends between the arms of the bracket 90 and is provided with lateral projections 132 pivotally mounted in the arms 90 and serving to support the secondary lever and associated parts in condition for pivotal movement to engage and disengage the contact bridges 122 and 124. A compression spring 134 is mounted between the secondary lever 130 and the inner wall of the frame 10 on the side of the pivotal mounting opposite the contact bridges 122, 124, thus serving to bias the contact bridges out of engagement with the contacts 118, 120, and 112, 114, respectively.

The secondary lever 130 is adapted to be operated during the snap action of the main actuating lever 64. Thus, interengaging means on the main lever 64 and the secondary lever 130 are provided and take the form of a rocker 136 mounted on a pivot 138 supported on the depending portion of an angular arm 140 projecting from the bracket 90 immediately below and inwardly of one of the arms thereof. The rocker 136 extends toward the main actuating lever 64 in position to be engaged thereby when over center snap action occurs. Preferably, the rocker 136 has a ramp 142 formed thereon and

the lever 64 is provided with a lateral projection 144 which will ride along the ramp 142 and serve to tilt the rocker 136 during the over center snap action of the lever 64.

In order to maintain the contact bridges 122, 124 in engagement with their respective contacts, the bias of the spring 134 is overcome by a latching arrangement now to be described. The underside of the rocker 136 is engaged by the free end of a U-shaped strip of spring metal 146 which is secured to the channel-shaped support 84 and has its free end spaced therefrom. The opposite end of the rocker 136 is thus urged about the pivot 138 toward a projection 148 which is formed on a depressed portion of the secondary lever 130. Latching engagement between the secondary lever 130 and the rocker 136 is secured by forming the end of the rocker adjacent the projection 148 with a notch 150 with which the projection 148 may engage. As shown in Figs. 2 and 6, the secondary lever 130 is in what may be termed the unlatched position, notch 150 being disengaged from the projection 148. In this position, the spring 134 has biased the secondary lever 130 from normal latched position so that the contact bridges 122, 124 are disengaged from their respective contacts. A button 152 is provided on the exterior of the cover 14 to reciprocate a pin 154 carried by and extending into operative engagement with the secondary lever 130 when the button 152 is depressed. The pin is normally biased out of engagement with the lever 130 by a compression spring 156 operative between the button and the cover 14. The pin 154 engages the lever 130 on the side thereof opposite the projection 148 and thus serves to pivot the lever against the bias of the lever spring 134.

Secured to the back of the L-shaped frame 10 is a housing 158 of insulating material. A pair of oppositely disposed screws 160 extending between the frame 10 and the housing 158 serve to secure these parts together. The housing 158 carries on one side thereof a pair of fixed contacts 162, 164 with which a movable contact bridge 166 is adapted to cooperate. The contact 164 is in the nature of a permanent connection inasmuch as a conductor 168 is permanently connected at one end thereto. The contact 162, however, is provided with terminal connections including the screw 170.

The contact bridge 166 is carried by a switch arm 172 of insulating material which is pivoted by a mounting 173 on a frame 174 secured by means of the screw 176 to the housing 158. A coil spring 178 operative between a projection 179 on the frame 174 and the switch arm 172 serves to bias the latter and therefore the contact bridge 166 carried thereby into engagement with the contacts 162 and 164. Disengagement of these contacts 162, 164 with the contact bridge 166 is effected by a pin 180 which extends from the mounting 173 through aligned apertures in the housing 158 and the frame 10 for engagement by the adjacent insulating plate 126 which is carried by the secondary lever 130. It is apparent that contact bridge 166 is either disengaged or engaged with its contacts simultaneously with the disengagement or engagement of contact bridges 122, 124 with their contacts.

The other portion of the housing 158 is provided with a pair of flexible switch arms 182, 184 carrying contacts 186, 188, respectively at their free ends. The switch arms 182, 184 are secured at the opposite ends to the housing 158 by screws 180 and are provided with separate terminal con-

nections 192. The contacts 186, 188 are adapted to cooperate with contacts 194, 196, respectively, which are secured to the housing 158 by screws 197. The conductor 168 is connected at its opposite end to the contact 196 as a permanent connection while a similarly permanent connection is made by the conductor 198 at one end thereof with the contact 194. The opposite end of the conductor 198 is permanently connected with the contact 112 which also connects with one end of conductor 110 as described.

The flexible switch arms 182, 184 are adapted for conjoint operation to disengage from the contacts 194, 196. To this end, a projection 200 extends from the base of the housing 158 intermediate the switch arms 182, 184 and serves as a pivot point for one end of an actuating plate 202 of insulating material which underlies the switch arms 182, 184. The other end of the plate 202 is supported on the end face of a hollow projection 204 which carries a pin 206 adapted for free reciprocation therein. The pin 206 extends through suitable aligned apertures in the wall of the housing 158 and frame 10 for engagement by the end 25 of the operating bar 42 as shown clearly in Fig. 7. The arrangement is such that upon longitudinal movement of the operating bar 42 in a right-hand direction as viewed in Fig. 7, the pin 206 will move the plate 202 and serve to disengage the contacts 186, 188 from their related fixed contacts 194, 196.

Referring now more particularly to the wiring diagram shown in Fig. 8, it will be apparent that the pair of terminals 192 may be connected by line 35 wires 208, respectively, to a source of electrical energy such as a house current supply. A heating element A has one end connected by a wire 210 to the terminal 171 and the opposite end connected to one end of a second heating element B which 40 has its opposite end connected by a wire 212 to the terminal 116. A ground wire 213 is tapped into the connection between the heating elements A and B.

Heat distributing means in the form of an electric motor-operated fan or blower (not shown) is provided for circulating heated air through the load of clothing which is placed in the drying drum (not shown) to be dried. The motor may also operate the drum which revolves during the 50 drying operation. The motor is shown in Fig. 8 as having one terminal connected to ground and the opposite terminal connected by a conductor 214 to the terminal 108. Further description of 55 circuits for the heating elements and the motor will be given in connection with the description of the operation of the device, which follows.

In the operation of the device it may be assumed that the dial 30 is in the "off" position so that the cam element 38 has forced the operating 60 bar 42 inwardly to engage and move the pin 206 and thus operate the flexible switch arms 182, 184 to disengage the contacts 186, 188 thereon from the contacts 194, 196, respectively. Thus, the current is broken on both sides of the line and 65 movement of the handle 28 in a counter-clockwise direction is required to disengage the operating bar 42 from the cam element 38.

Rotation of the handle 28 in a counter-clockwise direction from "off" to a preselected temperature setting will serve to cause longitudinal movement of the stud 48 to the right, as viewed in 70 Fig. 2. This also causes movement of the diaphragm 54 and the button 52 to the right but is insufficient to operate the main actuating lever 64 and cause snap action of the control lever 76.

Thus, the auxiliary switching means for the motor comprising the contact bridge 102 remains in position where the contacts 104, 106 are disengaged. However, the operating bar 42 no longer causes disengagement of contacts 186, 188 from contacts 194, 196, respectively. The button 152 is then operated to cause the pin 154 to engage and move the lower end of the secondary lever 130, thus overcoming the bias of the spring 134 and permitting the spring arm 146 to tilt the rocker 136 and engage notch 150 with projection 148. The secondary lever 130 is thus latched in its forward position with the contact bridges 122 and 124 in engagement with the contacts 118, 120 and 112, 114, respectively. Due to the forward movement of the secondary lever 130 the contact bridge 166 is simultaneously moved by the contact arm 172 under bias of the spring 178 into engagement with the contacts 162, 164 as previously explained.

A circuit may now be traced on Fig. 8 from the right-hand line wire 208, terminal 192, contacts 188, 196, wire 168, contact 162, contact bridge 166, contact 164, wire 210, heating element A, heating element B, wire 212, contact 114, contact bridge 124, contact 112, wire 198, contact 194, contact 186, terminal 192 and left-hand line wire 208. The circuit for both the heating elements is thus complete.

At the same time, a circuit for the motor may also be traced by way of a left-hand line wire 208, terminal 192, contact 186, contact 194, wire 198, contact 112, wire 110, contact 120, contact bridge 122, contact 118 and wire 214 to one terminal of the motor which, as stated, has its other terminal grounded. Thus, the circuit for the motor is completed and operation of both the heating element and the motor can occur.

When the temperature in the drying appliance reaches that which has been preselected on the dial, then the control will operate thermostatically. That is, the diaphragm 54 will expand sufficiently to cause the overcenter snap-action of the control lever 76. It should be noted at this point that the control device can be adjusted so that upon a rise in temperature at the bulb 60 the auxiliary switching means for the motor comprising contacts 104, 106 and contact bridge 102 become engaged just below the preselected setting. However, as long as such contact engagement occurs substantially simultaneously with the disengagement of the other contacts due to the snap-action the operation of the motor will not be interrupted.

Thus, upon snap-action of the control lever 76 the projection 144 on the main actuating lever 64 tilts the rocker 136 and releases the secondary lever 130. The contact bridges 122 and 124 carried by this lever 130 are thereby disengaged from their related contacts simultaneously with disengagement of contact bridge 166 from its related contacts 162, 164 by operation of the pin 180. The heating elements A and B are therefore deenergized but the circuit to the motor is continued through the auxiliary switching means comprising contact bridge 102 and contacts 104, 106.

When the temperature at the bulb 60 drops an amount corresponding to the differential of the thermostat then the diaphragm 54 contracts sufficiently to cause overcenter snap-action in the opposite direction. The auxiliary switching means is therefore opened by the biasing means therefor comprising the spring 72 and the motor ceases to run.

It is thus apparent that the auxiliary switching means comprising contact bridge 102 and contacts

104, 106 is operated thermostatically and will be opened and closed according to the temperature at the bulb 60. The switches controlled by the secondary lever 130, that is, contact bridges 122, 124 and 166 and associated contacts are operated thermostatically to open position but require manual resetting to closed position. Thus the heating elements remain deenergized until the control is manually operated.

15 It is further apparent that the motor will continue to run and will drive the fan and drum after the heating elements are cut out until the temperature at the bulb has dropped to a safe level. Thus, the clothes can then be handled without fear of burning the hands and at the same time an additional drying period is obtained.

The control is fully automatic. After the wet clothes are put in the appliance and the controls set as described, then the heating cycle and cooling down period will take place and thereafter the appliance will shut itself down. Thus, the appliance will operate safely with no attention on the part of the operator once the controls have properly been set. Cross reference is made to co-pending application of Weber and Garner, Serial No. 688,582, filed August 5, 1946.

It will be understood that various changes may be made in the details of construction and arrangement of parts and that the control device 30 may be utilized for useful purposes other than clothes drying controls. The push button control could be omitted and a sliding dial utilized in place thereof. The rotating motion of the dial could be used as described for setting the temperature and axial motion for bringing the switches into contact engaged position. This and other modifications may be made within the scope of the appended claims without departing from the spirit of the invention.

40 We claim:

1. A control device comprising switching means having open and closed positions for controlling an energizing circuit, switching means having open and closed positions for controlling a second energizing circuit, means for closing both said switching means to establish said circuits, auxiliary switching means having open and closed positions for controlling one of said circuits independently of said switching means therefor, means responsive to changes in a condition to be controlled, means for opening both said switching means upon a change in said condition affecting said condition responsive means and for substantially simultaneously closing said auxiliary switching means to maintain said one of said circuits, and means for opening said auxiliary switching means to discontinue said one of said circuits upon a further change in said condition affecting said condition responsive means.

2. A control device comprising switching means having open and closed positions for controlling an energizing circuit, switching means having open and closed positions for controlling a second energizing circuit, manually operable means for closing both said switching means to establish said circuits, auxiliary switching means having open and closed positions for controlling the first said circuit independently of said switching means therefor, means responsive to a condition to be controlled, means for opening both said switching means upon a change in said condition affecting said condition responsive means and for substantially simultaneously closing said auxiliary switching means to maintain said first

circuit, and means for opening said auxiliary switching means to discontinue said first circuit upon a further change in said condition affecting said condition responsive means.

3. A control device for electrical heat distributing apparatus comprising switching means having open and closed positions for controlling a heating circuit, switching means having open and closed positions for controlling a heat distributing circuit, means for closing both said switching means to establish said circuits, auxiliary switching means having open and closed positions for controlling said heat distributing circuit independently of said switching means therefor, temperature responsive means, means for opening both said switching means upon a change in temperature affecting said temperature responsive means and for substantially simultaneously closing said auxiliary switching means to maintain said heat distributing circuit, and means for opening said auxiliary switching means to discontinue said heat distributing circuit upon a further change in temperature affecting said temperature responsive means.

4. A control device for electrical heat distributing apparatus comprising switching means having open and closed positions for controlling a heating circuit, switching means having open and closed positions for controlling a heat distributing circuit, manually operable means for closing both said switching means to establish said circuits, auxiliary switching means having open and closed positions for controlling said heat distributing circuit independently of said switching means therefor, temperature responsive means, means for opening both said switching means upon a rise in temperature affecting said temperature responsive means and for substantially simultaneously closing said auxiliary switching means to maintain said heat distributing circuit, and means for opening said auxiliary switching means to discontinue said heat distributing circuit upon a further drop in temperature affecting said temperature responsive means.

5. A control device for electrical heat distributing apparatus comprising switching means having open and closed positions for controlling a heating circuit, switching means having open and closed positions for controlling a heat distributing circuit, means for biasing both said switching means to open position, means for overcoming said biasing means and closing both said switching means to establish said circuits, means for latching both said switching means in closed position, auxiliary switching means having open and closed positions for controlling said heat distributing circuit, means for biasing said auxiliary switching means to open position, temperature responsive means, and means for releasing said latching means to open both said switching means upon a change in temperature affecting said temperature responsive means and for substantially simultaneously overcoming the biasing means for said auxiliary switching means for closing the same to maintain said heat distributing circuit, said auxiliary switching means being opened by the biasing means therefor upon a further change in temperature affecting said temperature responsive means.

6. A control device for electrical heat distributing apparatus comprising switching means having open and closed positions for controlling a heating circuit, switching means having open and closed positions for controlling a heat distributing circuit, temperature responsive means ad-

justable to different temperature settings, adjusting means for said temperature responsive means including a reciprocable element for closing both said switching means to establish said circuits, auxiliary switching means having open and closed positions for controlling said heat distributing circuit independently of said switching means therefor, means for opening both said switching means upon a change in temperature affecting said temperature responsive means and for substantially simultaneously closing said auxiliary switching means to maintain said heat distributing circuit, and means for opening said auxiliary switching means to discontinue said heat distributing circuit upon a further change in temperature affecting said temperature responsive means.

7. A control device for electrical heat distributing apparatus comprising switching means having open and closed positions for controlling a heating circuit, switching means having open and closed positions for controlling a heat distributing circuit, means for biasing both said switching means to open position, temperature responsive means adjustable to different temperature settings, adjusting means for said temperature responsive means including reciprocable and rotatable means, said reciprocable means being operative for overcoming said biasing means and closing both said switching means to establish said circuits, means for latching both said switching means in closed position, auxiliary switching means having open and closed positions for controlling said heat distributing circuit, means for biasing said auxiliary switching means to open position, said position being established when said rotatable means is adjusted to a selected temperature setting, means for releasing said latching means to open both said switching means upon a change in temperature affecting said temperature responsive means and for substantially simultaneously overcoming the biasing means for said auxiliary switching means for closing the same to maintain said heat distributing circuit, said auxiliary switching means being opened by the biasing means therefor upon a further change in temperature affecting said temperature responsive means.

8. A heat control device for an electrical heating appliance having a heating element and a motor, comprising temperature responsive means for controlling operating temperatures in the heating appliance, switching means common to both the heating element and the motor and having open and closed positions for controlling separate heating and motor circuits, adjusting means for said temperature responsive means, manually operable means for closing said switching means and establishing said circuits, means for returning said manually operable means to an inoperative position, auxiliary switching means having open and closed positions for controlling said motor circuit, means for opening said switching means upon a change in temperature affecting said temperature responsive means and for substantially simultaneously closing said auxiliary switching means to maintain said motor circuit, and means for opening said auxiliary switching means to discontinue said motor circuit upon a further change in temperature affecting said temperature responsive means, said switching means and said auxiliary switching means remaining open irrespective of subsequent temperature changes affecting said temperature responsive

11

means until said manually operable means is operated from said inoperative position.

9. A control device for drying apparatus having an electrical heating element and an electric motor, comprising switching means for controlling energization of the motor and the current supply to the heating element, auxiliary switching means for controlling energization of the motor, and temperature responsive means for opening the first said switching means at a predetermined temperature caused by operation of the heating element and simultaneously closing said auxiliary switching means.

10. A control device as claimed in claim 9 wherein said temperature responsive means is 15

12

adapted to open said auxiliary switching means in response to a temperature drop below said predetermined temperature.

VICTOR WEBER.
WILLIAM S. KUNZLER.
